Inventor:

J. V. Rowlett
Per C. A. Roberts, Atty.

United States Patent Office.

J. V. ROWLETT, OF RICHMOND, INDIANA.

Letters Patent No. 96,970, dated November 16, 1869.

IMPROVEMENT IN STRAW-CUTTERS.

The Schedule referred to in these Letters Patent and making part of the same.

To all whom it may concern:

Be it known that I, J. V. ROWLETT, of Richmond, in the county of Wayne, and State of Indiana, have invented an Improved Straw-Cutter; and I do hereby declare that the following is a full and exact description thereof, reference being had to the accompanying drawings, making a part of this specification.

The nature of my invention relates to the combination, with the knife of a straw-cutter, constructed as herein described, and pivoted at the upper end to a swinging arm, of a lever that is grasped by the hand, and by means of which the knife is operated.

Also, my invention consists in the peculiar arrangement of the feeding-devices, as will be hereinafter described.

In the accompanying drawings—

Figure 1 is an end elevation of my improved straw-cutter, and

Figure 2 is a side view of the same.

Similar letters in the different figures refer to corresponding parts.

One end of the knife A is secured by a bolt to the arm P, that is pivoted at I, above the knife, and the other end of said knife is likewise secured by bolts to the lever R.

The lever R is pivoted to the frame-work of the box, below the knife, and also extends beyond the point at which the knife is pivoted, forming a handle, to be grasped by the hand of the operator.

By means of this arrangement, an easy drawing-cut is produced, the knife assuming successively the positions indicated by dotted lines on the drawing, fig. 1.

The arm P has a broad bearing at I, to prevent its springing and allowing the knife to be forced away from the cutter-bar X.

The said arm P is further extended beyond the pivot I, and the slotted plate E, attached thereto, by means of a pin and set-screw so adjusted that the

said plate may be extended more or less beyond the end of the arm, as required.

The function of the plate E is to operate the feeding-mechanism, which it does, when the knife is raised, by depressing the lever D, to which are attached two pawls, d d', operating upon ratchets, v v', on the feed-rollers.

The height to which the knife is raised being constant, by properly adjusting the plate E, any required length of feed may be readily obtained.

The lever D and pawls d d' are returned, after a feed is made, by the spiral spring y.

The cutter-box B and supporting frame-work, together with the feed-rollers and cutter-bar, may be made in any suitable manner, the cutter-bar having a bearing provided at its upper part, to which the arm P is pivoted, as shown at I, fig. 1.

I do not claim, broadly, a knife pivoted to a swinging arm above and a similar arm below; but

What I claim, and desire to secure by Letters Patent, is—

1. The lever R, constructed with an extension or handle for the operator, as shown and described, and used in combination with a straight knife, A, and swinging arm P, substantially in the manner and for the purpose set forth.

2. The slotted plate E, when used in combination with the arm P, for the purpose of operating the feeding-mechanism, substantially as described.

3. In combination with the arm P and plate E, the lever D, pawls d d', and spring Y, when constructed and operated as herein set forth.

4. The swinging arm P, having an extension beyond the pivot I, as described, when said extension is used to operate the feeding-mechanism, substantially as set forth.

J. V. ROWLETT.
